SELF-THREADING SHUTTLE

Starling I. Bright, Greer, S. C.

Application June 3, 1947, Serial No. 752,219

3 Claims. (Cl. 139—223)

1

This invention relates to self-threading shuttles.

My invention is concerned with a self-threading shuttle of the same general type as that disclosed in United States patent to Davis 1,573,227.

A specific object of my invention is to devise an improved construction of side delivery eye for the shuttle.

Another object of my invention is to improve the threading block to prevent catching of the thread between the side flange of the block and the wall of the block receiving chamber.

My invention will be explained in connection with the accompanying drawing in which

Figure 1 shows a shuttle construction of the prior art, such as that shown in the Davis patent referred to above.

Figure 2 is a side elevational view of the front end of a shuttle equipped with my improved side delivery eye.

Figure 3 is a plan view of Figure 2, a portion thereof being shown in section along a horizontal plane passing through the center of the side delivery eye.

Figure 4 is a perspective view of the improved side delivery eye shown from a point to the rear and somewhat in front of the delivery eye.

Figure 1 shows the general type of shuttle on which my invention is an improvement. 1 indicates the shuttle body which is provided with a bobbin chamber 2 in which is mounted the bobbin 3 in the usual manner. The front end of the body 1 is provided with a recess 4 having parallel side walls and forming a chamber for receiving a threading block 5, the upper face of which is grooved to provide an open thread guiding groove or passage. A thread casting and guiding element 6 is supported near the rear end of the block 5 and has the free end thereof positioned within the open thread guiding passage of block 5. The block is also provided with the usual thread directing apron 5b.

The shuttle body 1 is provided with a thread delivery slot located in the front end of the threading block recess 4 and connecting this recess to one side of the shuttle. A delivery eye 7 is positioned within the delivery slot and comprises a metallic sleeve-like element having a slot in one side thereof as shown generally at 23 in the Davis Patent 1,573,227. The outer end of the delivery eye opens into a thread guiding groove 9 formed in the side of the shuttle body. After leaving the shuttle eye, the thread from the bobbin 3 is alternately drawn along the groove 9 in one direction and then in the other. Eventu-

2

ally, the thread causes excessive wear in the wooden surface of the groove 9 on both sides of the delivery eye, and this causes undue roughening of the thread guiding surface and eventually makes it necessary to replace the shuttle. One object of my invention is to improve the delivery eye construction to avoid this difficulty.

My improved delivery eye construction is shown in Figures 2, 3 and 4, and involves a thread guide plate 10 seated in a recess formed in the side of the shuttle body and extending over a portion of the thread guiding groove 9 both to the rear and front of the side delivery slot, as more clearly shown in Figure 3. The rear end of the plate 10 extends beyond the cross-bolt 8 and is secured in position by means of the cross-bolt which passes through an aperture formed in the plate as shown in Figure 3. The forward end of plate 10 is suitably secured to the shuttle body 20 by suitable means such as the screw 11. Plate 10 is provided with a slotted aperture in alignment with the thread delivery slot and carries on its rear face a thread guiding tube 12 which forms the boundary of the aperture and extends into the delivery slot and serves the same function as the side delivery eye 7 in Figure 1. The guide plate 10 and the guide tube 12 may be formed from a single piece of sheet metal by usual stamping and drawing operations, or the two parts may be formed integrally by a casting operation. It will also be understood that the two parts 10 and 12 may be formed separately and joined together in any suitable manner.

As shown in Figures 3 and 4, the plate 10 is curved in conformity with the surface of the thread guiding groove 9, and the plate provides a metallic surface for the groove 9 over portions thereof extending forwardly and rearwardly of the side delivery eye. This construction provides a smooth, hard wearing surface for the thread A coming from the bobbin 3, and thereby avoids the objectionable roughening of the surface of the groove as explained above.

In prior constructions according to Figure 1, there is a tendency for the thread A from the bobbin 3 to catch at the point B between the side flange 5a of the threading block 5 and the adjacent wall of the block recess 4. In order to overcome this objectionable feature, I extend the side flange of the threading block along the wall of the block recess and partly into the bobbin chamber 2 as shown at 5a' in Figure 3. This construction places the corner or end of the flange 5a' in a position such that the thread can-

not be caught between the corner or end of the flange and the shuttle body.

It will be understood that the cross-bolt 8 serves two functions; first, it serves the usual function of securing the threading block 5 in proper position in the recess for the block in the shuttle body, and secondly, it serves to clamp the rear end of the guide plate 10 to the shuttle body. It will also be understood that the guide tube 12 is joined to the plate 10 in such a manner that the surfaces of these two elements merge into each other in a smooth rounded surface, as shown in Figure 3, in order to avoid undue friction against the thread.

I claim:

1. In a self-threading shuttle having a wooden body provided with a recess in which is secured a threading block, and a thread delivery slot connecting said recess with a thread groove formed in the side surface of said wooden body, and said block is secured in said recess by a cross-bolt, the improvement which consists in a thread guide plate mounted in a recess formed in the side surface of said body and extending over a portion of said thread guiding groove both to the front of and the rear of said side delivery slot, said guide plate having a slotted aperture arranged in alignment with said delivery slot, and a slotted thread guiding sleeve secured to said plate around said aperture and being positioned in said thread delivery slot, the rear portion of said guide plate extending back to said cross-bolt and being clamped to said body by said cross-bolt.

2. In a self-threading shuttle having a wooden body provided with a recess in which is secured a threading block, and a thread delivery slot connecting said recess with a thread groove formed in the side surface of said wooden body, and said block is secured in said recess by a cross-bolt, the improvement which consists in a thread guide plate mounted in a recess formed in the side surface of said body and extending over a portion of said thread guiding groove both to the front of

and the rear of said side delivery slot, said guide plate having a slotted aperture arranged in alignment with said delivery slot, the portion of said guide plate forming the boundary of said slotted aperture being extended into said delivery slot and providing a smoothly rounded delivery eye, and the rear portion of said guide plate extending back to said cross-bolt and being clamped to said body by said cross-bolt.

3. In a self-threading shuttle having a wooden body provided with a recess in which is secured a threading block, and a thread delivery slot connecting said recess with a thread groove formed in the side surface of said wooden body, and said block is secured in said recess by a cross-bolt, the improvement which consists in a thread guide plate mounted in a recess formed in the side surface of said body and extending along and forming a portion of said thread guiding groove both to the front of and the rear of said side delivery slot, said guide plate having a slotted aperture arranged in alignment with said delivery slot, and the rear portion of said guide plate extending back to said cross-bolt and being clamped to said body by said cross-bolt.

STARLING I. BRIGHT.
